WINDOW GUARD

John L. Mayer, Kansas City, Mo.

Application October 22, 1945, Serial No. 623,786

9 Claims. (Cl. 160—34)

1

This invention relates to window guards of the character combinable with window frames defining an opening wherein slideable sash are positioned and is a continuation in part of my co-pending application, Serial No. 583,303, filed March 17, 1945, for "Guarded window assembly."

The primary aim of this invention is to provide a guard for windows of the sliding sash type wherein the folding or collapsible grille of the guard may be released from its anchored condition and bodily raised as a unit with the window sash while it is housed behind a suitably disposed apron.

Another important aim of this invention is to provide means for releasing the lower portion of the grille from its attachment with the window sill, which means is operable only when the window sash to which the upper part of the grille is attached, is in the lowered or closed position.

This invention has for a yet further object to provide structure for locking the sash and grille of the guard against movement at any point in the path of travel of the sash for the purpose of holding the window open part way and precluding unauthorized persons from shifting the window sash toward the open or closed position from a place outside the building of which the window is a part.

Other aims of the invention are important and will be made clear during the course of the following specification referring to the accompanying drawings, wherein:

Fig. 1 is an elevational view of a window assembly having a guard thereon that is made pursuant to the present invention.

Fig. 2 is a view similar to Fig. 1 but showing the lower portion of the window frame with the sash and guard in a closed condition.

Fig. 3 is an enlarged fragmentary detailed elevational view of the lower portion of the sliding window sash to which the upper part of the collapsible grille is attached.

Fig. 4 is a fragmentary vertical sectional view on an enlarged scale taken on line IV—IV of Fig. 1 and looking in the direction of the arrows.

Fig. 5 is a similar sectional view taken on line V—V of Fig. 2.

Fig. 6 is a fragmentary detailed sectional view taken on line VI—VI of Fig. 1 and looking in the direction of the arrows.

Fig. 7 is a fragmentary sectional view taken on line VII—VII of Fig. 1 and looking in the direction of the arrows.

Fig. 8 is a sectional view on an enlarged scale

1 taken on line VIII—VIII of Fig. 1 and looking in the direction of the arrows.

Fig. 9 is a fragmentary detailed enlarged sectional view taken on line IX—IX of Fig. 1, and Fig. 10 is a fragmentary detailed perspective view illustrating the locking element and manner of releasing the locking bar from a point near the top of the window sash.

The window guard chosen for illustration embodies the preferred form of the invention and is chosen to be associated with a window frame generally designated by the numeral 12 within which is slidably mounted a pair of sashes 14. The lower sash 14 slides to the position shown in Fig. 1, from the closed position illustrated in Fig. 2 and in so doing, the grille 16 of the guard is extended to be positioned across the opening formed by window frame 12 and that is normally closed by sash 14 when the latter is shut. This grille 16 comprises a number of horizontal members 18, each provided with a bearing 20 to slide along vertical rails 22, one of which is mounted at each side of window frame 12. Rails 22 each comprises a tube 24 and a rod 26 reciprocably mounted in tube 24 for movement toward and from a position where its lower end will interlock anchoring strip 28 and locking bar 30. A perforation 32 in strip 28 registers with a hole 34 in bar 30 when said bar is in a position to allow normal movement of grille 16, as sash 14 is raised.

30 A series of links 36 pivotally secured as at 38 to members 18 have their ends articulated as at 40 and the rivet 40, which pivotally joins links 36, has its heads on each end thereof housed within opposed channels forming each member 18. These channels embrace bearings 20, as clearly shown in Fig. 10.

40 Anchoring strip 28 is secured to sill 42 of window frame 12, as shown in Figs. 4 and 5, and the ends of this strip 28 are rebent to threadingly receive the lower end of tube 24 through which rod 26 is passed. There is a locking bar 30 at each end of member 18 attached to the lowermost portion of grille 16 and each bar 30 has a pintle 44 secured thereto and projected through a slot 46 in the outer flange of the said lower member 18.

45 An apron 46 having a bayonet slot 48 therein adjacent to each pintle 44 allows movement of pintle 44 to shift bar 30 when the guard or grille 16 is in the position shown in Fig. 2. Such shifting of pintles 44 will move bar 30 toward and from a position where the hole and perforation 34 and 32 respectively will register to receive

55 rod 26.

The upper end of tube 24 is threadingly engaged by a bracket 50 that has a swingable L-shaped member 52 pivotally mounted thereon as at 54. A notch 56 receives rod 26 when the parts are in the position shown in Fig. 10 and head 58 on rod 26 precludes the rod from dropping back into the locked position when member 52 is in the place shown in Fig. 10. The upper end of member 52 has a salient 60 thereon that is eccentric to the pivotal connection 54 and which strikes the surface of sash 14 when it is in the raised position shown in Fig. 1 to preclude the lifting of rod 26 to a place where it will unlock bar 30 and allow disconnection of the lower part of grille 16 from sill 42. Thus a safety feature is present in that the lower part of grille 16 cannot be disengaged from sill 42 when sash 14 is raised. Member 52 assumes the position shown in Figs. 1 and 2 when rod 26 is interlocking bar 30 and strip 28. In such position head 58 lies beneath member 52 and cannot be lifted until the member is swung around pivot 54 and out of the way of head 58. Such swinging cannot occur when the sash 14 is open. Guide rails 22 are rigid to window frame 12 and means is provided for interlocking both the sash 14 and grille 16 in any position throughout the path of movement of the sash. This means comprises a latch member 62 in the form of a hook partially circumscribing each rail 22 and extending through apron 46 to threadingly receive a manually manipulable knob 64. When the knob is loosened no tight engagement between member 62 and rail 22 is established and free relative movement of these parts is permitted. If for example sash 14 is stopped part way up and it is desired to secure the sash and grille assembly in that place, knobs 64 are tightened and member 62 will grip rails 22 to preclude accidental movement.

In many instances it is desired to open sash 14 without having grille 16 extend across the opening formed in window frame 12. Under such conditions and with sash 14 in the lowered position, arms 52 are swung out from above heads 58, rods 26 are moved up out of engagement with locking bars 30, and member 52 is allowed to swing back where notch 56 receives rod 26. In this position bars 30 are moved inwardly from beneath the inturned ends of anchor strip 28 by manually manipulating pintles 44 within bayonet slots 48. When the sash is lifted again pintles 48 will hold the lowermost member 18 of grille 16 in a connected condition with respect to apron 46 and all of members 18 in a collapsed unitary condition will be lifted with sash 14. The grille 16 will be completely housed behind apron 46 and between this said apron and the lower portion of window sash 14.

This possibility of manipulation allows both upper and lower sashes 14 to be washed as is now the custom, and by manipulating these sashes to different exposed positions in the opening formed by window frame 12. When lower sash 14 is elevated, only the upper member 18 receives a lifting or motivating force to extend all parts of grille 16. The connection between apron 46 and uppermost member 18 is through the medium of a bifurcated bearing 66 between the legs whereof hook 62 is confined, as shown in Fig. 6.

From the foregoing it will be apparent that disconnection of the lower portion of grille 16 cannot occur when sash 14 is elevated and therefore, the safe guarding of the opening across which grille 16 is extended, will always be possible without fear of unauthorized persons on the out-

side of the window disconnecting the grille from its anchored condition. It will also be manifest to one skilled in the art that the bodily lifting of the collapsible grille 16 may occur with minimum amount of manipulation and that the collapsed grille 16 may be hung from the lower portion of the window sash without obstructing the view through the glassed portion of sash 14 nor through the opening formed within frame 12. This because apron 46 is but slightly wider than the width of the lower element of sash 14 and the entire guard is confined to an area across the opening of window frame 12 which is not objectionably greater than that occupied by the lower frame member of the sash 14.

The broad ideas embodied in the window guard illustrated and described are capable of embodiment in structure having arrangements of parts and appearances different than those illustrated and therefore, it is desired to be limited only by the spirit of the invention and scope of the appended claims.

Having thus described the invention what I claim as new and desire to secure by Letters Patent is:

1. A guard for windows having a reciprocable sash and a frame defining an opening for the sash, said guard comprising an expansible grille having its lower portion anchored to the sill of the window frame and its upper portion secured to the window sash to extend over the opening formed by the frame as the sash is moved to the open position; a guide rail for the grille at each side of the opening; and structure for interlocking the guide rails and a portion of the grille to secure the latter and the sash to which the grille is secured against movement.

2. A guard for windows having a reciprocable sash and a frame defining an opening for the sash, said guard comprising an expansible grille having its lower portion anchored to the sill of the window frame and its upper portion secured to the window sash to extend over the opening formed by the frame as the sash is moved to the open position; a guide rail for the grille at each side of the opening; and structure for interlocking the guide rails and a portion of the grille to secure the latter and the sash to which the grille is secured against movement, said interlocking structure being adapted to function at any desired point along the length of the guide rails between the closed and open positions of the sash.

3. A guard for windows having a reciprocable sash and a frame defining an opening for the sash, said guard comprising an expansible grille having its lower portion releasably anchored to the sill of the window frame and its upper portion secured to the window sash to extend over the opening formed by the frame as the sash is moved to the open position; a guide rail for the grille at each side of the opening; and means for releasing the lower portion of the grille from the sill of the window frame and for coupling that said lower portion to the upper portion of the grille, whereby upon raising the sash, the grille will be bodily lifted thereby in a collapsed condition.

4. A guard for windows having a reciprocable sash and a frame defining an opening for the sash, said guard comprising an expansible grille having its lower portion releasably anchored to the sill of the window frame and its upper portion secured to the window sash to extend over the opening formed by the frame as the sash is moved to the open position; a guide rail for the

grille at each side of the opening; and means for releasing the lower portion of the grille from the sill of the window frame and for coupling that said lower portion to the upper portion of the grille, whereby upon raising the sash, the grille will be bodily lifted thereby in a collapsed condition, said means for releasing the lower portion of the grille from the sill of the window frame including structure operable to the releasing position only when the window sash is in substantially closed position.

5. A guard for windows having a reciprocable sash and a frame defining an opening for the sash, said guard comprising an expansible grille having its lower portion releasably anchored to the sill of the window frame and its upper portion secured to the window sash to extend over the opening formed by the frame as the sash is moved to the open position; a guide rail for the grille at each side of the opening; structure for interlocking the guide rails and a portion of the grille to secure the latter and the sash to which the grille is secured against movement; and means for releasing the lower portion of the grille from the sill of the window frame and for coupling that said lower portion to the upper portion of the grille, whereby upon raising the sash, the grille will be bodily lifted thereby in a collapsed condition.

6. A guard for windows having a reciprocable sash and a frame defining an opening for the sash, said guard comprising an expansible grille having its lower portion releasably anchored to the sill of the window frame and its upper portion secured to the window sash to extend over the opening formed by the frame as the sash is moved to the open position; a guide rail for the grille at each side of the opening; and means for releasing the lower portion of the grille from the sill of the window frame and for coupling that said lower portion to the upper portion of the grille, whereby upon raising the sash, the grille will be bodily lifted thereby in a collapsed condition, said means for releasing the lower portion of the grille from the sill of the window frame including a locking element having a part exposed for manual manipulation at a point above the lower edge of the sash to prevent access thereto from outside the window when the sash is open.

7. A guard for windows having a reciprocable sash and a frame defining an opening for the sash, said guard comprising an expansible grille having its lower portion anchored to the sill of the window frame and its upper portion secured to the window sash to extend over the opening formed by the frame as the sash is moved to the open position; a guide rail for the grille at each side of the opening; and an apron mounted on the uppermost portion of the grille and depending therefrom to one side of the grille to house the grille when in a collapsed condition, and structure for interlocking the guide rails and the apron to secure the latter, the grille and the sash against movement toward or from the open or closed positions.

8. A guard as set forth in claim 6 wherein the exposed part is a rod reciprocably mounted in each guide rail, and the locking element is a shiftable bar at the bottom of the grille.

9. A guard for windows having a reciprocable sash and a frame defining an opening for the sash, said guard comprising an expansible grille having its lower portion releasably anchored to the sill of the window frame and its upper portion secured to the window sash to extend over the opening formed by the frame as the sash is moved to the open position; a guide rail for the grille at each side of the opening; an apron mounted on the uppermost portion of the grille and depending therefrom to one side of the grille to house the grille when in a collapsed condition; and means for releasing the lower portion of the grille from the sill of the window frame and for coupling that said lower portion to the apron, whereby upon raising the sash, the grille will be bodily lifted therewith and in a housed condition behind the apron.
